UNITED STATES PATENT OFFICE.

LEOPOLD KAHN, OF NEW YORK, N. Y.

DESIGN FOR THE ORNAMENTATION OF SHEET METAL.

SPECIFICATION forming part of Design No. 21,696, dated July 5, 1892.

Application filed June 2, 1892. Serial No. 435,317. Term of patent 3½ years.

To all whom it may concern:

Be it known that I, LEOPOLD KAHN, of New York city, in the county and State of New York, have invented a new and original 5 Design for the Ornamentation of Metal, of which the following is a full, clear, and exact description.

My design has reference to the ornamentation of sheet metals such as are used in making articles of ornament and of a certain degree of utility, such as toilet articles, candlesticks, comb-trays, and analogous constructions, and the design is produced in such a way as to make the metal resemble fabric.

15 Figure 1 is a plan view of a strip of metal, showing my design. Fig. 2 is an end or sectional view showing in outline the relative positions of the strips of metal which make up the design, these figures being deemed necessary to fully illustrate the design.

20 The leading feature of my design is the al-

ternating strips of ribbon-like and lace-like metal. The sheet of metal showing my design is made up of alternating strips of ribbon-like figures 10 and lace-like figures 11, 25 the figures being placed parallel with each other and the figures 10 being made to imitate moiré ribbon. The lace-like figures 11 may be made to simulate different varieties of lace; but they have preferably scalloped 30 edges, and the edges next the ribbon-like figures 10 over-lap said figures, so that when viewed in end elevation the lace-like figures appear in relief.

I claim—

35 The design for the ornamentation of metal herein shown and described.

LEOPOLD KAHN.
